UNITED STATES PATENT OFFICE.

JOHN THOMSON AND CHESTER H. EVANS, OF SAN FRANCISCO, CAL.

STEAM PUMPING-ENGINE.

SPECIFICATION forming part of Letters Patent No. 243,814, dated July 5, 1881.

Application filed November 7, 1879.

To all whom it may concern:

Be it known that we, JOHN THOMSON and CHESTER H. EVANS, both of the city of San Francisco, State of California, have invented 55
5 a new and useful Improvement in Steam Pumping-Engines, of which the following is a specification.

The invention relates to that class of pumps used in deep wells or for submerged pumps located in the water and used to force water up. 10

The invention will be understood as set forth in the following specification and claims.

In the accompanying drawings, Figure 1 is 15 an elevation of the engine and pump together. Fig. 2 is a detail of the engine.

P represents the pump-barrel, r the piston-rod, L the discharge-pipe. i i are suspending- 20 rods supporting the plate d, on which rests the spring D, and bears against the head l on the rod r above. The rods i i may be adjusted by means of bolts on their lower ends to any length.

Fig. 1 shows a pump and engine combined, the object of the engine being to impart a reciprocating motion to the pump-rod r, the engine E having a cross-head, H, which gives a rotary motion to the shaft F', and so that a continuous rod, r, can be used for the pump P and the piston of the engine E; also, in the 30 manner of connecting the crank that rotates the shaft F' and fly-wheel F to the cross-head.

In Fig. 1, F is the fly-wheel, hung on a shaft, on the opposite end of which shaft is fixed the crank K. The said crank is provided with a 35 wrist-pin which works into half-boxes b', that are made to slide in the cross-head H. In between one of the boxes and the cross-head H is inserted a wedge, w, which is provided with a gib-head, and through said head is passed a 40 stud which is rigidly screwed into one of the boxes b' that is on the side next to w. The stud o is provided with a nut, which, being screwed down, presses the wedge between the box b' and cross-head H, thus tightening the 45 box b' on the crank-pin, and also tightening the box in the slide of the cross-head H. In order to keep the wedge firm in its place we insert a string of thin washers around the bolt o and between the head of w and the box b', 50 so that as the nut is screwed down tightly it

closes the head of w firmly on the washers between the head and box b', thus making it fit closely in the cross-head H, and causing the box b' and wedge to be rigidly connected together. In case slackness should occur, we remove one or more of the washers and screw the wedge down on the remainder. In this case we use a common slide-valve (not shown) which is worked by an eccentric placed on the shaft of the fly-wheel. 60

The weight of the piston and long rod superadded to the force of the engine make the downward stroke of the piston much more forcible than the upward, and to counterbalance this we have provided a counterbalancing spring, D. This spring is a coil wound about the rod r, and resting upon a strap or plate, a, which is swung from the frame of the pump by the rods i i. At its upper end the springs bear against a collar, l, rigidly fixed to the rod r. This prevents a sudden descent, and, recoiling, aids in lifting the piston on the upward stroke. 65

Fig. 2 shows the cross-head and the manner of connecting the same to a continuous rod, r, 70 also the bearings B B, eccentric f, and crank k, around the fly-wheel shaft, also the arm p, which slides in the frame m, and keeps the cross-head H from turning. 75

We purpose to make the pump the subject 80 of a separate application.

What we claim as our invention is—

1. The cylindrical pump and engine E, having a continuous piston-rod, r, in combination with the head H and boxes b', wedge w, stud o, 85 and washer t, operating the crank k, thereby rotating the shaft F', fly-wheel F, and valve-eccentric f, substantially as shown and described.

2. The counterbalance-spring D coiled round 90 the rod r, and sustained by the adjusting-rod i and by the plate d, said spring pressing against the collar l, secured to rod r, as set forth.

JOHN THOMSON.
CHESTER HEPBURN EVANS.
